UNITED STATES PATENT OFFICE.

JOHN WACZULA, OF NEW YORK, N. Y.

COMBINATION LATHE-TOOL.

1,300,204.

Specification of Letters Patent.

Patented Apr. 8, 1919.

Application filed April 20, 1918. Serial No. 229,780.

To all whom it may concern:

Be it known that I, JOHN WACZULA, a subject of the King of Hungary, (first naturalization papers having been obtained,) and a resident of the city of New York, borough of Manhattan, in the county and State of New York, have invented a new and Improved Combination Lathe-Tool, of which the following is a full, clear, and exact description.

This invention relates to a combination lathe tool and it has for its general objects to provide a comparatively simple, inexpensive and useful tool-holding means of such design that a plurality of tools or cutters can be used one at a time for enabling a great variety of work to be done.

A more specific object of the invention is the provision of a tool holder having a novel form of head whereby a cutter-holding gooseneck, a boring tool or cutters may be mounted therein in various positions, the clamping means in the head being such that the adjustments can be easily and quickly effected.

Another object of the invention is the provision of a novel form of gooseneck whereby a plurality of cutters can be clamped thereto, one at a time, by a single clamping bolt.

With such and other objects in view, the invention comprises various novel features of construction and arrangement of parts which will be set forth with particularity in the following description and claims appended hereto.

In the accompanying drawing, which illustrates certain embodiments of the invention and wherein similar characters of reference indicate corresponding parts in all the views,

Figure 1 is a side view showing the gooseneck combination;

Fig. 2 is a plan view thereof with a portion broken away to illustrate details of construction;

Fig. 3 is a vertical section on the line 3-3, Fig. 2;

Fig. 4 is a side view of the gooseneck separated from the holder and having a cutter clamped therein;

Fig. 5 is a sectional view on the line 5-5, Fig. 6, showing a cutter clamped in the holder without the gooseneck;

Fig. 6 is a side view of Fig. 5, with the head in section; and

Fig. 7 is a horizontal view showing a boring tool clamped in the holder.

Referring to the drawing, A designates the holder and B the gooseneck. The holder A comprises a bar-like shank 1 having a head 2 disposed slightly at an angle to the length of the shank, viewing the holder in side view, as in Fig. 1. This head has a longitudinal slot 3 extending from one side face to the other, whereby the head is divided into upper and lower jaws 5 and 6. The head has an opening or passage 7 extending from the top surface to the bottom and which is of round cross-section, and the head is also provided with a horizontal passage 8 which is coincident with the slot 3; or in other words, the inner faces of the jaws 5 and 6 have recesses struck from a common center so that a clamping bolt or a boring tool can be gripped between the jaws.

The gooseneck B comprises a rectangular head 9 which has a gooseneck shank 10 connected with the top of the head, and the substantially vertical straight portion 11 of the gooseneck is adapted to enter the opening 7 in the head of the tool holder, and the gooseneck is clamped rigidly in place by a bolt 12 which passes through the passage 8 of the tool holder, and this bolt has a recess 13 which constitutes a shoulder for gripping the portion 11 of the gooseneck, to thereby clamp the latter rigidly in place when the nut 14 is tightened.

The head 9 of the gooseneck attachment has a horizontal recess 15 in its side to receive a cutter 16, which latter is clamped by a bevel surface or shoulder 17 on the head 18 of a clamping bolt 19 which passes horizontally through the head 9, the top edge 20 of the cutter 16 being formed with a bevel. When the nut 21 of the bolt 19 is tightened the shoulder 17, by gripping the top edge of the cutter 16, clamps the latter firmly in the recess 15. Besides the passage 22 extending from side to side of the head 9, the latter also has a horizontal passage 23 extending from the front to the rear, or transversely to and intersecting the passage 22, such passage 23 serving to receive a cutter 24, as shown in Fig. 4.

The bolt 19 has a recess 25 which aligns with the passage 23, and one wall of the recess

forms a shoulder 26 which is adapted to engage the side of the cutter 24 so as to clamp the latter in the passage 23 when the nut 21 of the bolt 19 is tightened, it being understood that in this instance the cutter 16 is detached. In other words, only one cutter is used at a time on the head of the goose-neck.

In order to clamp a cutter directly in the holder A, a clamping bolt 27 is inserted in the passage 7 of the head 2, and in this bolt is a passage 28 which aligns with the recess 3 of the head 2, so that the cutter 29 can be inserted between the jaws 5 and 6 and through the opening 28. When the nut 30 of the bolt 27 is tightened the cutter 29 is firmly clamped in position. The cutter 29 can be set at any angle within a range of one hundred and eighty degrees more or less, and to effectively secure the cutter in different positions of adjustment interlocking means are provided between the head 31 of the bolt 27 and the bottom of the head 2 of the holder A. For instance, a projection or tooth 32 may be provided on the head 31 to engage in a recess 33 on the head 2. The tightening of the nut 30 causes the jaws 5 and 6 to firmly grip the cutter 29 to prevent vibration or shifting. The same bolt 27 is utilized when a boring tool 34 is employed in the holder A, as shown in Fig. 7, the shank of the boring tool being inserted through the horizontal opening 8 of the head 2. The bolt 31 has a recess 35 which forms a gripping shoulder to bind the boring tool in the holder A when the nut 30 is tightened. Obviously other tools may be clamped in the holder A or gooseneck B, as necessity demands.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A tool holder comprising a member having a head formed with a slot extending from one side to the other and having a

passage extending from the top to the bottom and intersecting the slot, a cutter disposed in the slot and adjustable to different angles, and a bolt extending through the passage and having an opening through which the cutter passes, whereby the bolt clamps the cutter in different positions of adjustment. 60

2. A tool holder comprising a member having a head formed with a slot extending from one side to the other and having a passage extending from the top to the bottom and intersecting the slot, a cutter disposed in the slot and adjustable to different angles, a bolt extending through the passage and having an opening through which the cutter passes, whereby the bolt clamps the cutter in different positions of adjustment, and means between the bolt and holder for preventing the bolt from turning. 70

3. In a tool of the class described, a holder including a shank and a head, said head being provided with a passage extending from the top to the bottom and a passage extending from one side to the other, with the passages intersecting and in communication, and also having a slot extending across the head 85 from one side to the other and from one end inwardly, said slot being in the plane of the second-mentioned passage. 80

4. A combination tool including a head having a slot extending through the front 90 end thereof and through opposite sides of the tool, said slot being adapted to receive a cutter and permit of the latter being adjusted through an angle of approximately 180°, said head having also a transverse cutter-receiving passage extending from side to side thereof at said slot to intersect the latter; together with a clamping element extending through the head transversely to said slot and to said passage and having cutter-engaging means. 95

5. The combination of a holder, a gooseneck attachment clamped thereon, said attachment including a head having a recess in its side and a passage extending approximately parallel with the recess and a third passage extending transversely to the recess and second-mentioned passage, and a bolt extending through the last-mentioned passage and having separate shoulders, of which 105 one is adapted to be engaged with a cutter in the second-mentioned passage of the head and the other is adapted to be engaged with the cutter in the recess. 110

JOHN WACZULA.
